Primary Examiner — Stella Reid*Assistant Examiner* — Lauren Calve(74) *Attorney, Agent, or Firm* — Fitch, Even, Tabin & Flannery LLP(57) **CLAIM**

The ornamental design for a bowl, as shown and described.

DESCRIPTION

FIG. 1 is a perspective view of a first bowl showing our new design;

FIG. 2 is a front elevational view of the bowl of FIG. 1, the rear elevational view being identical;

FIG. 3 is top plan view of the bowl of FIG. 1;

FIG. 4 is a right side elevational view of the bowl of FIG. 1, the left side elevational view being identical;

FIG. 5 is a bottom plan view of the bowl of FIG. 1;

FIG. 6 is a perspective view of a second bowl showing our new design;

FIG. 7 is a front elevational view of the bowl of FIG. 6, the rear elevational view being identical;

FIG. 8 is top plan view of the bowl of FIG. 6;

FIG. 9 is a right side elevational view of the bowl of FIG. 6, the left side elevational view being identical; and,

FIG. 10 is a bottom plan view of the bowl of FIG. 6.

Broken line disclosures in the figures are for illustrative purposes only and form no part of the claimed design.
